UNITED STATES PATENT OFFICE.

FREDERICK SOMERSET NIAS, OF BRIGHTON, ENGLAND.

WINDMILL ACCELERATOR.

Application filed September 20, 1926, Serial No. 136,480, and in Great Britain October 20, 1925.

This invention relates to windmills and has for its object a construction designed to render them more efficient than hitherto.

According to my invention I provide the 5 sails of windmills each with a series of auxiliary blades whereby an acceleration of speed is obtained.

In the preferred manner of carrying out the invention, the accelerator blades are 10 made of flat plates, rectangular in form and arranged on the active or working face of each windmill sail or blade. The accelerator blades are preferably attached or mounted at a common inclination to the 15 windmill blades and along the trailing edges thereof. The members of each series of auxiliary blades will thus be in parallelism with their edges disposed at an incline with respect to the edges of the windmill blade 20 carrying them.

To enable the invention to be fully understood I will describe it by reference to the accompanying drawing, in which:

Figures 1 and 2 are, respectively, a front 25 elevation and a side elevation of the sails of a windmill provided with accelerator blades in accordance with the invention.

Figure 3 is a section on the line 3—3, Figure 1.

30 *a, a, a, a* are the windmill sails or blades radiating from the boss or hub *b* and inclined with respect to their common plane in the usual way so that they will be caused to rotate in the said plane by the action of the wind on their front faces in a direction normal to the said plane.

35 *c, c* are the auxiliary or accelerator blades which I apply to the active or working faces of the sails *a*, at a common inclination thereto, these accelerator blades being made of rectangular flat plates and applied in series along one edge, and preferably the trailing edge of each sail *a*. The members of each series of blades *c* are in parallelism, with 40 their edges inclined with respect to the edges of the sail *a* carrying them. In the drawing, the longitudinal edges of each series of accelerator blades *c* are at a common inclination of 45

about 30° to the trailing edge of the sail *a* on which they are mounted, as indicated in 50 Figure 1, whilst the said blades have a common inclination, as shown clearly in Figure 3, of about 45° to the said sail.

I do not restrict myself to the said angles of inclination as they may be varied in accordance with requirements and the varying angles of the sails with respect to the direction of the wind.

Claims:

1. A windmill sail comprising a set of 60 propeller blades mounted upon a hub for rotation therewith, and a plurality of parallel auxiliary blades mounted upon the windward face of each propeller blade near its trailing edge, said auxiliary blades projecting forwardly from the windward faces of the propeller blades.

2. In combination with a windmill sail comprising a set of propeller blades mounted upon a hub for rotation therewith, each 70 blade having a plane windward face, of a plurality of auxiliary blades mounted upon the trailing edge portion of the windward face of each propeller blade.

3. In combination with a windmill sail 75 comprising a set of propeller blades mounted upon a hub for rotation therewith, of a plurality of auxiliary overlapping parallel blades mounted upon the trailing edge of the windward side of each propeller blade, said 80 auxiliary blades forming acute angles with said trailing edges.

4. A sail of the wind wheel type comprising a set of plane propeller blades, each blade being provided with a set of plane 85 auxiliary blades upon the trailing edge of its windward side.

5. A fan shaped wheel comprising a set of plane blades mounted upon a hub for rotation therewith, each blade being inclined 90 to present a surface for impact with air, and a series of parallel overlapping plane auxiliary blades secured on said impact surface of each of said main blades near the trailing edge thereof.

FREDERICK SOMERSET NIAS.
